LIGHTER WITH MAGNETIZED TELESCOPIC TIP

Taro Yanai, 13-4, Shirakawa 1-chome,
Koto-ku, Tokyo, Japan

Filed Dec. 19, 1974, Ser. No. 534,484

Term of patent 14 years

Int. Cl. D27—05

U.S. Cl. D27—38

FIG.2

FIG.1

FIG.3

FIG. 4

FIG. 5

FIG. 1 is a perspective view of a lighter with magnetized telescopic tip embodying my new design;

FIG. 2 is a top plan view thereof;

FIG. 3 is a side elevational view thereof showing the opposite side of the perspective;

FIG. 4 is a rear elevational view thereof;

FIG. 5 is a bottom plan view thereof; and

FIG. 6 is a partially broken, perspective exploded view showing the telescoping effect and the lighting member of the lighter.

The lighter is broken away in FIG. 6 for convenience of illustration.

FIG. 6

I claim:

The ornamental design for a lighter with magnetized telescopic tip, as shown and described.
